CANDLESTICK ORNAMENT

Edward B. Wolfsohn, Forest Hills, N.Y., assignor to Nated Corp., Forest Hills, N.Y., a corporation of New York

Filed Apr. 29, 1960, Ser. No. 60,385

Term of patent 14 years

(Cl. D48—2)

Fig. 1 is a top plan view of a candlestick ornament showing my new design; and Fig. 2 is a perspective view thereof.

I claim:

The ornamental design for a candlestick ornament, substantially as shown.
